UNITED STATES PATENT OFFICE.

LINWOOD M. ANDREWS, OF CHICAGO, ILLINOIS.

DESIGN FOR A STAND MIRROR.

Application filed March 21, 1927. Serial No. 21,233. Term of patent 7 years.

To all whom it may concern:

Be it known that I, LINWOOD M. ANDREWS, a citizen of the United States of America, residing at Chicago, in the county of Cook and State of Illinois, have invented a new, original, and ornamental Design for Stand Mirrors, of which the following is a specification, reference being had to the accompanying drawing, forming part thereof, in which the figure is a perspective view of a stand mirror embodying my new design.

I claim:

The ornamental design for a stand mirror, as shown.

In witness whereof I affix my signature.
LINWOOD M. ANDREWS.
